Attorney

UNITED STATES PATENT OFFICE.

JOHN JENSEN, OF HOUSTON, TEXAS.

TIE HOLDER.

Application filed September 23, 1926. Serial No. 137,298.

This invention relates to tie holders and more particularly to a device for holding ties of the four-in-hand type without the necessity of tying the same.

5 An important object of the invention is to provide a device of this character which will facilitate application and proper adjustment of the tie and which, if so desired, may be so constructed as to give the tie held 10 thereby the appearance of having been tied in the usual manner.

A further object of the invention is to provide a device of this character which may be readily and cheaply constructed and 15 which is readily applied to and removed from the tie.

These and other objects I attain by the construction shown in the accompanying drawing, wherein for the purpose of illustration is shown a preferred embodiment of 20 my invention and wherein:—

Figure 1 is a front elevation showing a tie holder constructed in accordance with my invention applied to a tie;

25 Figure 2 is a section on the line 2—2 of Figure 1;

Figure 3 is a section on the line 3—3 of Figure 1;

30 Figure 4 is a plan view of the holder removed;

Figure 5 is a side elevation thereof;

Figure 6 is a front elevation of the holder showing a covering applied thereto of the same material as employed in the construction 35 of the tie.

Referring now more particularly to the drawing, the numeral 10 generally designates a tapered tube substantially oval in cross section. Within this tube a partition 11 is 40 disposed which, at the larger end of the tube, extends across the tube at substantially the center thereof and in the same general direction as the minor axis of the tube. At its lower end, this partition extends transversely of the tube upon the major axis thereof, so that the partition thus provides two openings through the tube which parallel one another and the major axis of the tube at the lower end of the tube and which 45 parallel one another and the minor axis of

the tube at the upper end thereof. The partition is preferably slightly offset with respect to the major minor axes of the tube, so that one of the openings is larger than the other, the larger opening being arranged 55 at what is to be the front face of the tube.

In the use of the device, the smaller end of the tie is introduced to the larger opening 12 at the lower end of the tube, drawn through the upper end of the tube, then returned and introduced to the upper end of the smaller opening 13 and pulled through the lower end thereof. The loop thus provided at the upper end of the tube is enlarged until it is of a size permitting it to 60 be passed over the head of the wearer and the tie placed in position in the collar. After the tie is properly placed, the tube is slid up until it occupies its proper position 65 with relation to the collar.

70 Where the holder is to be sold as an accessory to the tie, it is preferably provided with a covering 14 of the same material as is employed in the construction of the tie. Where it is to be sold as a separate article 75 of jewelry, the outer face of the tube may be suitably ornamented, as indicated at 15.

Since the construction hereinbefore set forth is obviously capable of a certain range of change and modification without materially departing from the spirit of the invention, I do not limit myself to such specific structure except as hereinafter claimed.

I claim:—

80 A tie holder comprising a tapered tube 85 adapted for the passage of the ends of the tie, said tube being substantially oval in cross section and a partition within the tube and extending longitudinally thereof to divide the tube into two openings for the 90 reception of the ends of the tie, said partition at the upper end thereof extending transversely of the tube upon the minor axis thereof and at its lower end extending 95 transversely of the tube upon the major axis thereof.

In testimony whereof I hereunto affix my signature.

JOHN JENSEN.
